United States Patent Office.

WILLIAM POLYBLANK, OF CLEVELAND, OHIO.

Letters Patent No. 88,903, dated April 13, 1869.

IMPROVEMENT IN OIL-CANS.

The Schedule referred to in these Letters Patent and making part of the same.

To all whom it may concern:

Be it known that I, WILLIAM POLYBLANK, of Cleveland, in the county of Cuyahoga, and State of Ohio, have invented certain new and useful Improvements in Oil-Cans; and I do hereby declare that the following is a full and complete description of the same, reference being had to the accompanying drawings, making part of this specification, in which—

Figure 1 is a perspective view of the can.

Figures 2, 3, 4, and 5 are detached sections, to which reference will be had.

Like letters of reference refer to like parts in the different views presented.

This invention has for its object, the construction of an oil-can in such way, that the said can shall combine strength and safety with convenience of shape for storage and transportation; also, providing the same with the means of discharging its contents wholly, and with facility.

In fig. 1, A represents the can, which, in shape, is an oblong square. The shape, however, may be varied, as well as the size, as circumstances may demand.

One of the characteristics of this can, is the peculiar manner of connecting the top and bottom, A' and B, to the sides, or body C, and which is as follows:

The edge of the top and bottom is struck up, and formed into a hook, or U-shaped lap, D, fig. 3, whereas the top and bottom-edge of the sides are slightly bent outwardly, forming a flange, a, which is made to correspond in its angle to that of the lap D, and into which it is fitted, as shown at a', which represents a vertical section of the can, showing one edge of the top and side locked into each other.

The lap, or hook-part of the joint, is then compressed together, thereby tightly embracing the flange-like edge of the side. This being done, the joint is then further secured by soldering, either by the use of the ordinary soldering-iron, or by the immersion of the same in a bath of melted solder. In this way, a strong and durable joint is obtained, which will effectually prevent the sides from being pressed in by any ordinary force. By means of the shoulder b, formed around the centre edge of the top, and against which the edges of the sides rest, and are thereby outwardly braced, the joint is relieved from strain, in consequence of any external pressure upon the sides of the can.

A further improvement consists in providing the can with an outlet, and means for ventilation.

In the hole made in one corner, or elsewhere in the top of the can, is fitted a thimble, D', fig. 2, for the admission and retention of the cork. Around the upper end of the thimble, are air-holes e, the practical use of which will presently be shown.

It will be obvious, that by providing the can with the thimble, a cork, or bung can be fitted tightly therein, it being compressed by the slight taper given to the

thimble, and will therefore be held as tightly as a cork in an ordinary bottle.

The bung is inserted in the hole, so that it shall be even with the top, over which is then soldered a plate of tin, thereby making the opening permanently tight, for transportation.

It is well known, that on drawing fluids from a full bottle or cask, in consequence of the external pressure of the air upon the fluid, it will not flow out in a full, unbroken stream, the air passing into the vessel through the same outlet from which the contents are flowing, produces a throbbing, or pulsatory flow, which causes the fluid to run down upon the outside of the vessel, in a slow and dilatory manner, and if the vessel is full, it will cease to flow until ventilated.

In order to facilitate the flowing out of the contents of the can, it is ventilated by means of the air-holes e, above referred to, said holes allowing the air to enter the can immediately at the opening, and therefore is not compelled to traverse the length of the thimble to reach the inside.

By this means of supplying air to the can, the throbbing, or pulsatory flowing of the oil is obviated; but, instead, will run out with a full, steady, and unbroken stream.

Fig. 4 represents a supplementary thimble, having in its side a deep slot, e. The purpose of said thimble is to provide a projecting lip, or nozzle, for the outlet of the can, into which it is inserted, as shown in fig. 1, in which figure, E represents the thimble. By the use of this thimble, the oil is carried out further from the end of the can, thereby preventing its trickling down under the opening. The slot e allows the air to pass into the can through the air-holes, with which it is brought into open relation.

Fig. 5 represents a supplementary thimble, provided with a long curving spout, or discharging-tube, which carries the oil still further from the can, and which is found very convenient for the purpose of filling vessels, having a small mouth.

It will be obvious that, for ordinary purposes, the supplementary thimble and discharging-tube F will not be needed, as the contents of the can may be drawn off without them with facility, and without waste.

What I claim as my improvement, and desire to secure by Letters Patent, is—

1. The perforated bung-tube, or thimble D', in combination with the can A, substantially as and for the purpose described.

2. The combination of the discharging-tube F and supplementary thimble E, in the manner as and for the purpose set forth.

WM. POLYBLANK.
